No. 632,090.

T. G. BENNETT.

Patented Aug. 29, 1899.

BOLT GUN.

(No Model.)

(Application filed Apr. 3, 1899.)

UNITED STATES PATENT OFFICE.

THOMAS G. BENNETT, OF NEW HAVEN, CONNECTICUT, ASSIGNOR TO THE
WINCHESTER REPEATING ARMS COMPANY, OF SAME PLACE.

BOLT-GUN

SPECIFICATION forming part of Letters Patent No. 632,090, dated August 29, 1899.

Application filed April 3, 1899. Serial No. 711,504. (No model.)

To all whom it may concern:

Be it known that I, THOMAS G. BENNETT, of New Haven, in the county of New Haven and State of Connecticut, have invented a new 5 Improvement in Bolt-Guns; and I do hereby declare the following, when taken in connection with the accompanying drawings and the letters of reference marked thereon, to be a full, clear, and exact description of the same, 10 and which said drawings constitute part of this specification, and represent, in—

Figure 1, a broken plan view of a gun constructed in accordance with my invention with the breech-bolt in its closed and locked position; Fig. 2, a broken view of the gun in vertical longitudinal section with the breech-bolt in its closed and locked position and with its hammer in its fired position; Fig. 3, a 15 broken sectional view of the hammer; Fig. 4, a detached perspective view of the bolt with the hammer removed; Fig. 5, a broken detached reverse plan view of the barrel and its receiver extension; Fig. 6, a detached perspective view of the combined extractor, sear, 20 and trigger; Fig. 7, an enlarged view in vertical section on the line *a b* of Fig. 2, showing the friction-lock.

My invention relates to an improvement in that class of bolt-guns in which the bolt is located in a bolt-housing formed in a rearward extension of the gun-barrel itself.

More particularly my invention relates to an improvement upon a certain gun forming the subject-matter of an application for a 35 patent filed by John M. Browning February 17, 1899, and serially numbered 705,793.

The particular object of my present invention is to simplify the gun shown and described in the said Browning application by 40 reducing the number of its parts, whereby economy and simplicity of construction are secured.

With these ends in view my invention consists in a longitudinally and vertically movable combined extractor, sear, and trigger.

My invention further consists in the combination, with a combined extractor and sear, of a bolt coacting therewith and a friction-stop, the members of which are respectively 45 located upon the said combined part and bolt

in position to coact for frictionally holding the bolt in its closed and locked position.

My invention further consists in certain details of construction and combinations of parts, as will be hereinafter described, and 55 pointed out in the claims.

In carrying out my invention as herein shown I employ a combined part made in one piece and comprising a trigger A, a sear B, and an extractor C, the extractor being located at the forward end of the part, the trigger at the rear end of the part, and the sear about midway of the length of the part. The said part is located in a deep slot or chamber D, formed in the top of the stock E of the 60 gun and controlled and operated by a spring F, located in the forward end of the said chamber. The combined part has a vertical rocking movement as well as a longitudinal movement. For its vertical rocking movement it is furnished at its extreme forward end with a pivot-pin *a*, the ends of which bear against the lower face of the gun-barrel G at a point very little in rear of the forward end of a slot G', which, as shown in Fig. 5, extends from a point under the butt-end of the gun-barrel proper rearward through the tie or reach H, which connects the said end of the barrel with the bolt-housing H', which may be said to be separated from the barrel 65 by a loading-opening H'', located directly above the said reach or tie and extending downward by preference at least as far as the axial center of the barrel. The said slot G' receives the extractor C and the sear B, 70 permitting the former to engage with the heads of the cartridges, and permitting the latter to coact with the breech-bolt I and the hammer J, located therein. In speaking of the extractor C my design has been to identify the upwardly-extending hook formed at the forward end of the combined part. For the reception of the sear B the lower face of the bolt is provided with a longitudinally-arranged slot K, the rear end of the right-hand 75 wall of which has a lateral extension K', which permits the bolt to be rocked on its longitudinal axis when in its closed position by means of its laterally-arranged handle I', which moves back and forth in a longitudinal slot 80 85 90 95 100

H^3 , formed in the top of the bolt-housing H . The engagement of this handle with the forward edge of the housing at a point to the right of the slot H^3 locks the bolt against rearward longitudinal movement, while it is locked against forward longitudinal movement by the impingement of its forward end against the butt-end of the gun-barrel. When the handle I' is lifted into alignment with the slot H^3 , the turning movement of the bolt is stopped by the engagement of the left-hand side face B' of the sear with the rear portion of the left-hand wall of the slot K in the bolt at about the point K^2 , as shown in Fig. 4, whereby the turning movement of the bolt is stopped in the position of the registration of the bolt-handle with the forward end of the slot, preparatory to drawing the bolt rearward by the handle, at which time it enters the forward end of the slot and moves rearward therein. The sear of the said combined part is formed upon its upper edge with a cocking-nose b , which engages with the rear end wall of a cocking-slot b' , formed in the forward end of the cylindrical hammer L , which is located in the bolt I . When the hammer is drawn rearward into its cocked position, the spring F , before mentioned, immediately lifts upon the part, so that the upper edge of the sear B will enter the said slot b' and bring the nose b of the sear into engagement with the rear wall of the said slot, thus holding the hammer cocked. The gun is now fired by depressing the trigger A , the rear end of which is slightly projected out of the extreme rear end of the chamber D , formed in the gun-stock E . The trigger A , in one view of it, is nothing more than a long rigid rearward extension of the sear. The bolt is formed with a cylindrical chamber K^3 for the reception of the hammer J , the said chamber terminating at its forward end in a wall K^4 , formed with a small hole K^5 , which permits the forward extension through it of the firing-pin j . The hammer is formed with a longitudinal spring-chamber J' for the reception of a spiral hammer-spring M , the rear end of which normally impinges against the forward end of the stem N of a button N' , the said stem being entered into the extreme rear end of the hammer, in which it is held by the pin n , as shown in Fig. 3. The button N' is knurled and is grasped by the fingers for the cocking of the hammer. The hammer is connected to the bolt by means of a heavy pin O , which passes transversely through the rear end of the bolt and also passes through a longitudinal slot O' , formed in the rear end of the hammer, the forward end of this slot engaging with the pin to determine the degree to which the firing-pin may be retracted.

The rear end of the hammer-spring M is engaged for placing the spring under tension, with the pin O mounted in the bolt. It is apparent that if the said end of the spring were always engaged with the said pin the spring would exert a constant effort to push the

ring-pin forward and would hold it forward under tension. In order to avoid that objection, inasmuch as with the firing-pin projected to the limit of its extension through the forward end wall of the bolt the accidental discharge of cartridges might take place in the event of slamming the bolt into its closed position, I provide for normally holding the rear end of the spring out of engagement with the said pin. This I do by extending the stem N of the button N' inward beyond the pin, so as to form an abutment or seat for the rear end of the spring, thus holding the spring away from the pin for a distance represented by the projection of the end of the firing-pin j through the forward end wall of the bolt. The stem N is adapted to extend inward beyond the pin by forming the stem with a slot N^2 , Fig. 3, wide enough to receive the pin and deep enough to provide the play just above called for. Under this construction the hammer, together with the firing-pin, is free to move back and forth within the bolt entirely independent of the hammer-spring, so that if the bolt should be "slammed" forward in closing the hammer would be entirely free to move back without resistance, so that the forward end of the firing-pin will not project beyond the front face of the wall at the forward end of the bolt. Then if it happened that the bolt was closed with the firing-pin projected through its forward end the firing-pin would be pushed back without any indentation of the head of the cartridges, which it would not under these circumstances explode; but in cocking the gun as soon as the hammer has been retracted for a distance represented by the unoccupied forward end of the slot N^2 in the stem N the rear end of the hammer-spring is brought into contact with the pin O , which immediately begins to put the spring under tension.

For the purpose of frictionally holding the bolt in its closed and locked position I provide a friction-holding device comprising two headed pins P and P' , one being located in a recess P^2 , formed in the under face of the forward end of the bolt, and the other being located at the base of the rear end of the sear, as clearly shown in Fig. 6. These pins are relatively arranged, so that when the bolt is being turned into its locked position the pin P will ride from right to left over the pin P' in the combined part, which will at this time be forced downward against the tension of its spring F , which as soon as the pin P has ridden over the pin P' will lift the combined part again, whereby the two pins will hold the bolt in its locked position. Here I may remark that I provide sufficient play between the forward end of the combined part and the walls of the forward end of the slot G' and the front face of the bolt to permit the forward end of the combined part to move up and down sufficiently to permit one pin to snap over the other. This snapping movement of the two pins of course cannot take

place unless provision were made for the yielding of the forward end of the combined part. When the gun is unlocked, the pin P snaps from left to right over the pin P', at 5 which time the combined part retires downward slightly, as before.

It is apparent that my improved combined part, hammer, and friction-holding device are not necessarily used in conjunction in the 10 same gun, but that they may be used independently or in any desirable combination. I would therefore have it understood that I do not limit myself to the exact construction herein shown and described, but hold myself 15 at liberty to make such changes and alterations as fairly fall within the spirit and scope of my invention.

Having fully described my invention, what I claim as new, and desire to secure by Letters 20 Patent, is—

1. In a bolt-gun, the combination with a longitudinally-movable bolt, of a longitudinally-movable hammer located therein, and a combined extractor, sear and trigger located directly beneath the said bolt in a line parallel therewith, and adapted at its forward end to act as an extractor, for which purpose it is engaged by the bolt and moved forward and back, and adapted at its rear end, which extends rearwardly beyond the bolt, to act as a trigger, and constructed between its ends to act as a sear, for which purpose it is vertically moved for coaction with the said hammer.

35 2. In a bolt-gun, the combination with a bolt having a longitudinal chamber, of a hammer located in the said bolt and longitudinally chambered, a spring located in the hammer, a pin mounted in the rear end of the bolt and 40 passing through a slot in the hammer, and a stem entering the outer end of the hammer and adapted to extend inward beyond the pin so as to normally hold the outer end of the spring away from the pin, whereby the hammer is normally relieved of the tension of the 45 spring which is imposed upon it only when the hammer is drawn sufficiently rearward to permit the spring to impinge upon the pin.

3. In a bolt-gun, the combination with a longitudinally-movable and rotatable bolt, of a combined extractor and sear located below the bolt and adapted to be longitudinally and vertically moved, and a friction-holding device, the members of which are carried by the 55 bolt and combined part and arranged to hold the bolt in its closed and locked position.

4. In a bolt-gun, the combination with a longitudinally-movable and rotatable bolt, of a combined extractor and sear located below the bolt and adapted to be longitudinally and vertically moved, and coacting pin-heads mounted in the bolt and combined part in position to hold the bolt in its closed and locked position, the pin-head upon the bolt riding over the pin-head on the said part which yields 60 to permit the pin-head on the bolt to pass its pin-head after which the combined part recovers its position.

5. In a bolt-gun, the combination with a gun-barrel formed at its butt-end with an integral receiver extension comprising a bolt-housing and a reach, which latter is formed in its bottom portion with a long slot, of a longitudinally-movable and rotatable bolt mounted in the said housing, a hammer mounted in the 75 said bolt and projecting rearwardly beyond the same, and a combined extractor, sear and trigger, adapted at its forward end to act as an extractor, formed between its ends with a sear which passes upward through the said 80 slot into position for engagement with the hammer, and adapted at its rear end, which extends rearward beyond the rear end of the bolt, to be engaged and depressed for disengaging the sear from the hammer, the said 85 combined part being arranged under the bolt in line therewith.

6. In a bolt-gun, the combination with a gun-barrel formed at its butt-end with an integral receiver extension comprising a tubular bolt-housing and a reach, which latter is formed in its bottom portion with a long slot, of a longitudinally-movable and rotatable bolt, having a clearance-slot formed in it, a hammer located within the said bolt and projecting 95 rearwardly from the rear end thereof, and a combined extractor and sear located below the bolt in a line parallel therewith, and having its sear adapted to enter the clearance-slot in the bolt and coact with the hammer 100 for cocking the same, the said sear being also constructed to coact with one wall of the slot in the bolt for limiting the rotation of the bolt so as to stop it in proper position for its rearward longitudinal movement.

In testimony whereof I have signed this specification in the presence of two subscribing witnesses.

THOMAS G. BENNETT.
